UNITED STATES PATENT OFFICE.

GEORGE E. A. KNIGHT, OF PROVIDENCE, RHODE ISLAND.

FIRE-EXTINGUISHER.

SPECIFICATION forming part of Letters Patent No. 582,357, dated May 11, 1897.

Application filed October 9, 1896. Serial No. 608,327. (No model.)

To all whom it may concern:

Be it known that I, GEORGE E. A. KNIGHT, of the city of Providence, in the county of Providence and State of Rhode Island, have 5 invented a new and useful Improvement in Fire-Extinguishers; and I hereby declare that the following is a full, clear, and exact description of the same, reference being had to the accompanying drawings, forming part of 10 this specification.

This invention has reference to an improvement in the class of fire-extinguishers in which a fire-extinguishing liquid is placed under great gas-pressure and allowed to escape in 15 a fine stream with such force that the liquid can be thrown a considerable distance on the fire.

The object of this invention is to so construct the receptacle and so control the liquid 20 that a stream of the liquid can be readily directed on an incipient fire to extinguish the same and the gas-pressure maintained for an indefinite time.

The invention consists in the peculiar and 25 novel construction of the device and the combination of the parts, as will be more fully set forth hereinafter.

Figure 1 is a side view of the portable extinguisher, which is of greater length than 30 shown and therefore is shown with the central portion broken away. Fig. 2 is an end view showing the valve by which the discharge of the liquid is controlled. Fig. 3 is a sectional view of the upper end of the extinguisher, 35 showing the construction of the valve by which the liquid and gas is confined and its discharge controlled.

My improved fire-extinguisher is designed to be hung up at such points in places to be 40 protected as will enable persons about the premises to reach it and use it the instant an incipient fire is detected. To this end it is charged with liquid and gas under high pressure, and it is essential that this high pressure be maintained during a long period. The slightest leak or the accidental even slight opening of the valve would destroy the usefulness of the device at the critical moment. I have therefore constructed the valve 45 so that the internal pressure will hold the valve to its seat, also so that the valve can be locked firmly to its seat, and so that when

required the valve may be ground to its seat without removing the valve or discharging the gas.

55

In the drawings, *a* is a long tube or cylinder of such diameter as permits it to be readily grasped by one hand. *b* is the lower cap by which one end of the cylinder or tube *a* is closed. *b'* is the upper cap by which the other 60 end of the tube *a* is closed.

c is a ring secured at one side to the upper cap *b'*, by which ring the extinguisher may be suspended from a hook or nail until required for use.

65

d is a tube secured in the upper cap so as to project above the cap and extend down to near the lower end of the tube or cylinder *a*.

The gas used in this class of fire-extinguishers is usually carbonic-acid gas, and the fluid 70 usually contains matter held in solution or suspension which evolves carbonic-acid gas when thrown on the fire. To thoroughly mix these constituents, I provide a chamber in which the fluid is allowed to expand and mix 75 before the same is discharged.

Within the upper end of the tube *d* the cap *e* is secured. The bottom of this cap *e* is pierced with a hole of about the size of the discharge-opening. The upper end of the cap *e* is screw-threaded, the screw-thread extending above 80 the upper end of the tube *d*. The valve-casing *f* is internally screw-threaded to engage with the threaded end of the cap *e*. It is provided with the valve-seat *g* and above the 85 valve-seat with the enlarged annular groove *h*, from one side of which the discharge-opening extends through the nozzle *k*. The upper end of the valve-casing *f* is provided with the externally-screw-threaded packing-cup *l*, to 90 which the follower *m* is secured by screw-threaded engagement and by which the packing in the cup is compressed. The follower *m* is provided with the cup *n* and the screw *o*. The nut *p*, which is provided with the arms 95 *q*, has an annular groove into which the end of the screw *o* enters. The valve *r* is secured to or forms part of the valve-stem *s*, the upper part of which is screw-threaded and the upper end provided with the arms *t*. 100

The operation of the valve is as follows: When the extinguisher is charged, the turning of the handles *t* toward the left or against the sun draws the valve *r* against the seat *g*.

When now the arms *q q* and with them the nut *p* are turned to the right or with the sun, the valve and valve-stem are raised without turning and the valve is forced firmly against 5 the valve-seat. When the valve is to be opened, it may be done wholly by turning the nut *p* and handles *q q* in the reverse direction, thus moving the valve off from its seat without turning the same, or the valve may 10 be released from the close contact with the valve-seat by means of the nut *p* and arms *q q*, and then lowered by turning the valve and valve-stem by means of the arms *t t*. The valve *r*, valve-stem *s*, and the nut *p* may be 15 turned together while the valve is held to its seat, and thus the valve may be ground on the seat while the extinguisher is charged.

Having thus described my invention, I claim as new and desire to secure by Letters 20 Patent—

1. In a portable hand fire-extinguisher, the combination with the cylinder *a*, the end caps *b* and *b'*, the suspension-ring *c* and the central tube *d*, of the cap *e* secured in the tube 25 *d* and screw-threaded at its upper end, the valve-case *f* secured to the cap *e*, the valve-seat *g*, the annular groove *h*, the nozzle *k* connecting with the annular groove, a valve interposed between the valve-seat and the in-

ternal pressure, and the means, substantially 30 as described, for operating the valve, as described.

2. The combination in a portable fire-extinguisher with the tube *d*, of a mixing-chamber consisting of the cap *e* having a small 35 opening in its closed end, said cap being secured in the upper end of the tube *d*, the valve-case *f*, secured to the open end of the cap *e*, the valve-seat *g*, the annular groove *h*, the nozzle *k* the opening in which connects 40 with the annular groove *h*, the packing-cup *l* at the upper end of the valve-case *f*, the follower *m* for compressing the packing, the cup *n* on the upper part of the follower, the lock-nut *p* having an annular groove and provided 45 with the arms *q q*, the screw *o* for connecting the lock-nut *p* with the cup *n*, the valve *v* located in the cap *e*, the valve-stem *s* provided at its upper end with the arms *t t*, whereby the valve may be operated and locked and 50 the discharge of the liquid controlled, as described.

In witness whereof I have hereunto set my hand.

GEORGE E. A. KNIGHT.
